UNITED STATES PATENT OFFICE.

HIRAM EUGENE CHUTE, OF PERU, INDIANA.

OPERATING MECHANISM FOR REED-ORGANS.

No. 903,450.

Specification of Letters Patent.

Patented Nov. 10, 1908.

Application filed February 14, 1906. Serial No. 301,011.

To all whom it may concern:

Be it known that I, HIRAM EUGENE CHUTE, a citizen of the United States, and a resident of Peru, in the county of Miami 5 and State of Indiana, have invented a new and Improved Operating Mechanism for Reed-Organs, of which the following is a full, clear, and exact description.

This invention relates to certain improvements in operating mechanism particularly adapted for use in reed organs for controlling the notes of the organ, the octave coupler, and the like, and resides in the arrangement of this mechanism, whereby the 15 desired movement of said parts may be obtained and controlled by the treadle of the organ.

The invention involves various other features of major or minor importance all of 20 which will be fully set forth hereinafter and pointed out in the claims.

Reference is had to the accompanying drawings which form a part of this specification, in which drawings like characters of 25 reference indicate like parts in the several views, and in which

Figure 1 is a section of an organ provided with my improved operating mechanism; Fig. 2 is an enlarged sectional view illustrating a part of one of the keys and the octave coupler in connection therewith; Fig. 3 is an enlarged sectional view illustrating the two controllable reeds and the stops therefor; Figs. 4, 5, and 6, are elevational views illustrating various positions taken by the octave-coupler treadle; and Figs. 7, 8 and 9 are similar views illustrating the action of one of the stop treadles.

In the drawing applicant's invention is 40 shown in connection with an organ provided with the usual pumps or bellows 15, treadles 16 for operating the bellows, the suction box 17 the foundation reeds 18, the auxiliary reeds 19 and 20, the valves 21 controlling the communication between the reeds and the suction box, and operated from the keys 22 through the medium of pins 23, the valve 24 for permitting the passage of air through the reeds 18, the 45 valves 25 and 26 for controlling the reeds 19 and 20 respectively, the octave coupling levers 29 and the swinging supports 30 carrying said levers.

The invention consists of treadles and 55 connections especially adapted for operating

the valves 25 and 26 controlling the auxiliary reeds 19 and 20, and a treadle 31 and connections for operating the swinging carrier 30 controlling the octave coupler levers.

As best shown in Figs. 4, 5 and 6, the 60 octave coupler treadle 31 is articulated at its inner end with a vertically extending bar 32 having shoulders 33 and 34 on its upper portion. Said shoulders 33 and 34 are arranged on opposite sides. Above the shoulders 33 65 and 34, near the upper end of the bar, a shoulder 36 is formed at the same side on which is located the shoulder 34. Inclosing the bar and lying above the shoulders 33 and 34 is a loop 37 fastened rigidly to a rock 70 shaft 38. To this rock shaft is also fastened a crank arm 39, the crank arm 39 carrying pivotally a link 40 which extends upward and has its upper end pivotally connected to an arm 41 on a rock shaft 42 mounted in the 75 framing and having one or more arms 43 connected with the swinging carriers 30 so that upon the operation of the rock shaft the carriers will be caused to take the position shown by the dotted lines in Fig. 2, thus 80 throwing the octave coupler levers 29 into the path of the projections 44 on the keys 22.

Referring particularly to Figs. 4, 5 and 6, the operation of the octave-coupler-treadle-train may be traced as follows: Parts normally lie as shown in Fig. 4. Upon depressing the treadle the bar 32 is raised causing the shoulder 33 to rock the loop 37 and the rock shaft 38 and throw the parts 39 and 40 into the position shown in Fig. 5, in which 90 position the coupler-lever-carrier 30 will be raised as shown by the dotted lines in Fig. 2. Upon releasing the treadle the parts 31 and 32 will under the action of a spring 45 return to the position shown in Fig. 5. To 95 release the octave coupler and to permit the parts to return to normal or inactive position, a second movement of the treadle 31 should be effected thus bringing the parts to the position shown in Fig. 6 in which the shoulder 36 strikes a part of the framing of the organ and limits the upward movement of the bar 32, and the shoulder 34 strikes the loop 37 and throws the same over to the other side of the center of the rock shaft 38 100 as Fig. 6 illustrates, then upon releasing the treadle the bar 32 drops to the position shown in Figs. 4 and 5, and the link 40 and crank 39 are thrown down by gravity to the normal or inactive position. It will be 105 110

seen, therefore, that a single movement of the treadle throws the octave coupler into action and retains it in active position until it is desired to release the octave coupler, 5 whereupon a second movement of the treadle is effected and the parts are released as described.

The treadles and their connected trains for operating the valves 25 and 26 and controlling the reeds 19 and 20 are similar to each other, and one, for example the treadle 28 for operating the valve 26, is illustrated in Figs. 7, 8 and 9. To the said treadle a vertically extending bar 46 is pivoted, this 15 bar having at its upper portion shoulders 47 and 48 on opposite sides. The bar 46 is at its upper portion received in a loop 50 rigidly secured on a rock shaft 51 similar 20 essentially to the rock shaft 38. The rock shaft 51 carries a crank arm 52 to which a link 53 is joined (see Fig. 1). This link is connected at its upper end to an arm 54 which is attached to a swinging carrier 55, which is in turn connected with the valve 26 25 commanding the reeds 20. Upon depressing the treadle 27 the bar 46 will be moved upward, causing its shoulder 47 to engage the loop 50, and rocking the shaft 51 so as to throw upward the arm 52 and through the 30 medium of the parts 53, 54 and 55 raising the valve 26 admitting atmospheric pressure to the reeds 20. The parts will stay in this position excepting that the treadle and bar 46 will drop to the position shown in Fig. 8. 35 To release the rock shaft 51 and allow the valve 26 to close a second movement of the treadle will be effected, causing the shoulder 48 to engage the loop 50 and throw the rock shaft back (see Fig. 9) the same as described 40 in connection with the treadle 31 and its attachments. 56 indicates a stop screw or pin against which the end of the bar 46

may contact, and 57 indicates a spring similar to the spring 45 above described.

Various changes in the form, proportions 45 and minor details of my invention may be resorted to at will without departing from the spirit and scope thereof; hence I consider myself entitled to all such variations as may lie within the terms of my claims. 50

Having thus described my invention, I claim as new and desire to secure by Letters Patent:

1. In combination, a controllable part, a rock shaft in connection with said controllable part, said rock shaft having arms lying at opposite sides of the axis thereof, a movable member having shoulders respectively adapted to engage said arms of the rock shaft, means for operating said movable member, and the said movable member also having a shoulder at its upper extremity and a stop adapted to be engaged by said shoulder to limit the movement of the movable member. 65

2. In combination, a part adapted to be controlled, a reciprocating member, said member having shoulders at opposite sides thereof, means for operating the member, means adapted to be alternately engaged by 70 said shoulders and having connection with said part adapted to be controlled to operate the same, said reciprocating member also having a third shoulder at its upper extremity and a stop adapted to be engaged 75 by said shoulder.

In testimony whereof I have signed my name to this specification in the presence of two subscribing witnesses.

HIRAM EUGENE CHUTE.
